UNITED STATES PATENT OFFICE.

BENJAMIN TALBOT, OF MIDDLESBROUGH, ENGLAND.

METALLURGICAL FURNACE.

Application filed January 31, 1925, Serial No. 5,981, and in Great Britain April 24, 1924.

This invention relates to metallurgical furnaces and particularly to furnaces of large capacity for the manufacture of iron or steel, whether of the fixed or of the end-tilting or side-tilting types, and whether reversible or uniflow.

One object of the invention is to obviate the necessity of tapping the metal from a metallurgical furnace into a separate ladle.

10 Another object is to provide as part of the furnace structure means whereby the waste furnace gases may be utilized to pre-heat or melt pig iron, or deoxidizers such as ferro-manganese, spiegel or silicon prior 15 to their admixture with the main charge of the furnace.

Both these objects are achieved by constructing the furnace with one or more baths, preferably detachable from the main furnace 20 structure, which are in direct communication with the gas space of the said furnace and heated by the waste gases therefrom, and are controllably connected with the main hearth so that molten metal can be poured or 25 tapped from the hearth of the furnace, and if desired stored for a period of time before being poured from the bath.

These and other objects of the invention 30 will be more specifically described with reference to the accompanying drawings which illustrate regenerative tilting furnaces of the reversible type, but it is to be understood that these drawings are by way of illustration only and the invention is not to be considered 35 as restricted to furnaces of the type therein shown.

In these drawings Figs. 1 and 2 are a longitudinal vertical section and a sectional plan respectively of an end-tilting furnace, and 40 Fig. 3 is a section of same on line 3—3 of Fig. 1. Figs. 4, 5 and 6 are similar views of a side-tilting furnace, Fig. 6 being a section on line 6—6 of Fig. 4.

Referring to Figs. 1—3, in general construction the furnace is of the known type, being 45 adapted to rock on the roller bearing *a* (Fig. 1) when tilting is required, and fired at each end alternately by coke oven gas or oil supplied through burners *b* and air from a regenerator through flues *d* and ducts *c*. These flues and air ducts communicate with a bath *e* which is carried by the structure of the furnace, but can be removed when necessary for repair, and replaced, or can be exchanged 50 for a new one. At one end this bath is connected by a joint *f* in a vertical plane at

right angles to the axis of tilting, so as to permit this movement, with an elbow pipe or the like *g* (Figs. 2 and 3) leading to the regenerator, which is not shown since its construction and arrangement are of the usual kind. At the other end of the bath *e* is a discharge spout *h* which is normally tamped and one or more teeming nozzles *i* each normally closed by a stopper *l*. The communication between the bath and the hearth of the furnace is through a duct *l* leading from a tap-hole *l'* which may be closed by tamping applied by a tool inserted through door *m*.

The general operation of the furnace need 70 not be described as it is well known. When it is desired to withdraw molten metal from it, it is tilted in the desired direction and the tamping is removed from the duct *l* at the appropriate end of the furnace; metal is allowed to flow through the duct into the bath *e*, the stopper *h* being in place and the spout *h* duly tamped. The metal may then be teemed or poured as though the bath were 75 a ladle.

The slide damper *n* in a lateral extension of the bath *e* is normally raised; it is lowered to cut off radiation from the hot bath when the nozzle stoppers are being put in place.

The side-tilting furnace shown in Figs. 80 85 4, 5 and 6 is similarly constructed, but as the axis about which the tilting occurs is lengthwise of the furnace, the joint *f* between the bath *e* and the connection *g* is best made at the centre of the bath, as shown in Fig. 5; 90 the joint may open slightly during the tilting movement but the connection *g* being movable the joint is easily closed again.

Fixed furnaces embodying the present invention need not differ from the tilting furnaces of the drawings, except with respect to the supports, which are fixed.

Either arrangement of the joint *f* is suitable for a fixed furnace, although in that case a movable joint is not absolutely required, as 100 the furnace is not tilted, except for convenience of removing or changing the bath *e*.

When deoxidizers are charged into the bath *e*, they may be introduced through the doors *o*, preferably before the metal is transferred 105 to the bath, so that they may be preheated or melted. The bath or baths *e* may be utilized for melting, by the heat of the waste furnace gases, charges of pig-iron which, when melted, are transferred by means of ladles to the 110 main charge in the furnace hearth.

The invention is not limited to a single bath

associated with the furnace, whether at one part only or at more than one part. For instance, in the case of a furnace heated by producer gas which requires pre-heating, one 5 or more gas regenerators become a part of the installation, each requiring its cinder pocket which may be constructed to serve as a bath in the manner described.

It will be seen that the tap-holes in the 10 side walls of the furnace leading to the ducts *l* and the doors *m* provided in the opposite wall for applying the tamping rod are formed in laterally constricted portions of the furnace near the two ends of the latter.

15 Having thus described the nature of the said invention and the best means I know of carrying the same into practical effect, I claim:—

1. A metallurgical furnace having an auxiliary bath associated therewith, means for controlling the flow of liquid from the main hearth to said auxiliary bath and means for heating said bath by the waste furnace gases.

2. A reversible metallurgical furnace having an auxiliary bath at each end thereof and controllably connected with the main hearth of said furnace.

3. A reversible regenerative steel furnace having separate from its hearth and at each 30 end thereof a bath for melting metal or keeping metal molten, said baths being heated by waste gases from the furnace hearth.

4. A metallurgical furnace having an auxiliary bath associated therewith and positioned for heating by the waste furnace gases, 35 said auxiliary bath having a casting nozzle and stopper therefor, and damper means for screening said stopper from the main portion of the auxiliary bath.

5. A metallurgical furnace having an auxiliary bath associated therewith and positioned for heating by the waste furnace gases, 40 said bath having a lateral extension, and a casting nozzle and stopper in said lateral extension.

6. A regenerative reversible metallurgical furnace having supplementary receptacles associated therewith and controllably connected with the main hearth, said supplementary receptacles forming flues for waste heating gases from the furnace and being provided with means for pouring liquid therefrom. 45

7. A regenerative metallurgical furnace having a main hearth and an auxiliary hearth 50 heated by waste products of combustion from the main hearth, means forming an external channel connecting said hearths and means for flowing air in reverse directions alternately over said hearths. 55

8. A regenerative metallurgical furnace having a main hearth and an auxiliary hearth at each end thereof heated by waste products of combustion from the main hearth, and means for flowing air in reverse directions 60 alternately over said hearths. 65

9. A metallurgical furnace having associated therewith a supplementary receptacle forming a portion of a flue for waste heating gases from the furnace, and means positioned from the exterior of said furnace for controlling flow of liquid therefrom to said receptacle, said receptacle being provided with means for pouring liquid therefrom. 70

In testimony whereof I have signed my 75 name to this specification.

BENJAMIN TALBOT.
